Attorney

UNITED STATES PATENT OFFICE

EMIL A. MOLL, OF MASPETH, NEW YORK, ASSIGNOR TO CARMAN & CO., INC., OF NEW YORK, N. Y., A CORPORATION OF NEW YORK

ENVELOPE FOR LAUNDERED ARTICLES

Application filed November 21, 1929. Serial No. 408,810.

This invention relates to holders or envelopes for shirts and similar articles or goods, and has particular reference to such articles as are employed for returning goods from laundries to customers.

The practice in practically all large laundries is to attach similar identification tags or insignia to all of the goods belonging to a particular customer, and to leave all of such tags attached to the goods during all of the washing and ironing until all of the goods belonging to that particular customer are ready to be packaged for return to such customer. Then before the completion of the packaging, it is customary to remove all of such tags or insignia.

When goods such as shirts are enclosed in envelopes which conceal most, if not all of the articles, it interferes considerably with the process of removing the tags if each article must be slipped partly out of the container or envelope in order to gain access to the tag for removing it.

The object of the present invention is to provide an envelope which, although practically completely enclosing such an article as a shirt, possesses means whereby access may be had to the laundry identification tag, to remove such tag, without shifting the position of the shirt in the envelope.

With the above object in view, the invention consists in the envelope or container substantially as hereinafter described and claimed.

35 Of the accompanying drawing.

Figure 1 is a perspective view of an envelope in one embodiment of the invention.

Figure 2 is a similar view showing the flap in the back member turned over and providing an opening through which a portion of an enclosed shirt is accessible.

Figure 3 is a perspective view looking from the front of a packaged shirt.

Similar reference characters indicate similar parts or features in all of the views.

The envelope illustrated comprises a stiff back member 12, such as of suitable cardboard, and a flexible front member 13, preferably consisting of tissue paper, the side margins of the front member being folded

over the side edges of the back member and adhesively secured as at 14.

The envelope illustrated is somewhat of the type of that in Letters Patent 1,698,549, dated January 8, 1929 to La Bombard and Sidebotham, but the present invention is equally applicable to a wide variety of garment envelopes.

When a shirt is folded in the ordinary manner and enclosed in such an envelope the collar portion *a* (Fig. 3), and a portion of the shoulder or upper bosom *b* is exposed intentionally above the upper edge of the tissue or thin front member 13, while the skirt or tail portion of the article is folded back *as* and extends nearly up to the collar portion *a* and lies between the portions *a* *b* of the shirt and the stiff back member 12. This is the customary way of folding and enveloping a shirt. It is also customary to removably *70* connect the laundry insignia or identification tag with the skirt or tail portion of the shirt.

The present invention relates to a structure whereby access may be readily had to the *75* laundry insignia or identification tag attached to the shirt or other garment. In order that this may be done the back member 12 (Fig. 1) is provided with a curved cut 15, the ends of which are connected by a crease *80* line 16, whereby the area enclosed between the cut 15 and crease line 16 provides a flap 17 which, when turned out as illustrated by Fig. 2, leaves an opening in the stiff back member 12. This treating of the back mem- *85* ber to provide an opening is effected in a location or position to permit access to the laundry tag or insignia indicated in Fig. 2 at *d* as secured by suitable means such as a safety pin to the folded shirt or tail portion *c* of the *90* shirt.

When the garments are slipped into the envelopes in the usual manner, the flaps 17 of the envelopes will ordinarily lie closed as in Fig. 1. Then when all of the goods belonging to different customers are to be packaged, the flaps 17 are simply turned outward as illustrated by Fig. 2, and the identification tags *d* removed and the flaps 17 closed.

A further advantage of the opening in the *100*

back member 12 is that it facilitates the drawing of the shirt into the envelope during the packaging of the goods as it enables the fingers of an employee to reach through the opening and draw or smooth out the back portion of the garment.

I do not limit myself to the particular shape of opening illustrated, nor to the employment of a flap as the opening may be formed in any shape and may be effected by completely cutting out a portion of the cardboard. It is preferable to include the flap member since it will prevent dust or other objectionable matter gaining access to the interior of the container, whether the containers are filled with goods or are waiting in stock.

Having now described my invention, I claim:

1. A laundry package comprising a folded laundered garment, a small laundry tag serving as an identifying insignia and detachably secured to said garment in a location normally hidden from view during the wear of the garment and on the exterior of the folded garment, and a flat paper container enclosing said garment, said container having an opening for insertion and removal of the garment, and also having a relatively small opening registering with said tag for the purpose of removing the latter.

2. A laundry package comprising a folded laundered garment, a small laundry tag serving as an identifying insignia and detachably secured to said garment in a location normally hidden from view during the wear of the garment and on the exterior of the folded garment, and a container enclosing said garment, said container comprising a stiff back member and a flexible front member and having a permanently open end to permit the garment to be slidably mounted therein, the said back member having a relatively small opening registering with said tag for the purpose of removing the latter.

46 In testimony whereof I have affixed my signature.

EMIL A. MOLL.
